UNITED STATES PATENT OFFICE.

HUGH YOUNG AND H. GENGEMBRE HUBERT, OF NEW YORK, N. Y.

MACHINE FOR SCOURING AND POLISHING STONE.

SPECIFICATION forming part of Letters Patent No. 290,804, dated December 18, 1883.

Application filed March 13, 1883. (No model.)

To all whom it may concern:

Be it known that we, HUGH YOUNG and H. GENGEMBRE HUBERT, both of the city of New York, in the county and State of New York, 5 have invented a new and useful Improvement in Machines for Scouring and Polishing Stone, of which the following is a specification.

Our invention relates to that class of stone rubbing, scouring, and polishing apparatus in 10 which the stone to be operated upon is placed on a rotary bed or table, and is scoured or polished by means of sand or other abrading material, which is distributed over the surface. In machines of this class the sand is most com- 15 monly spread or distributed by hand, and hence is not uniformly or evenly distributed. Often through carelessness in feeding there is a great deficiency of sand on the bed, and at other times a surplus, resulting in waste of the 20 sand, and the operation of the machine is therefore not uniform.

The object of our invention is to enable the sand and abrading material to be fed to the bed with greater regularity and uniformity 25 than have before been possible, and in such quantities as will insure the most effective operation of the machine without causing a waste of sand or abrading material.

To this end our invention consists in the 30 combination, with the rotating bed of a stone rubbing or polishing machine, of a box or reservoir for scouring or polishing material, arranged between the center of the bed and its periphery, and composed of a body and a separated bottom, and mechanism deriving 35 motion from the machine itself for giving one of these elements a movement relatively to the other.

Between the body of the sand box or reservoir and its separated bottom there is formed 40 a delivery-opening, and as the body or bottom is moved the one relatively to the other the sand or other material escapes through this delivery-opening and is supplied uniformly 45 to the bed. The delivery of sand between the body and bottom of the box or reservoir may be effected by a continuous movement of the bottom in one direction and said bottom may consist of a disk or plate having a rotary motion or 50 a reciprocating motion, or of an endless apron or belt having a traveling movement continu-

ously in one direction below the body of the box or reservoir; or the bottom may consist of a fixed plate and the body have a reciprocating motion over said plate. 55

The constructions above described are all included in our invention when the box or reservoir is located as above described, and it or its separated bottom derives a motion from the machine itself. 60

In the accompanying drawings, Figure 1 is an elevation of a portion of a rotary bed and a sand-feeding apparatus embodying our invention. Fig. 2 is a plan thereof, the sand box or reservoir being shown in section. Figs. 65 3 and 4 are respectively a vertical section and an end elevation of a sand-feeding apparatus of modified form also embodying our invention; and Figs. 5 and 6 are sectional views of two other modified forms of apparatus also 70 embodying our invention.

Similar letters of reference designate corresponding parts in all the figures.

We will first describe the apparatus shown in Figs. 1 and 2. 75

A designates the rubbing or polishing bed, which is usually of iron, and is fixed on a vertical shaft, A'. This shaft is supported in an upright position in bearings, which are not hereshown, and it is to be rotated by any suitable gearing, such as is commonly employed in rubbing or polishing beds. 80

B designates the frame-work of the feeding apparatus, which is supported on or fixed to a beam or timber, B', extending across and 85 above the bed A. This frame will of course be considerably varied in form to suit the different forms of feeding apparatus which we may employ. The feeding apparatus comprises a sand box or reservoir composed of a body, C, and a bottom, C', separated from the body, so that one may have a movement independently of and relatively to the other. In this box or reservoir a supply of sand or other abrading material, a, is contained. The body 90 C is to be attached to any suitable fixed supports between the center of the bed A and its periphery, and the bottom C', which, as shown, consists of a circular plate or disk, is fixed on a vertical shaft, D, supported in a step-bearing, b, in the frame B. 95

Upon the shaft D, below the bottom C', is

fixed a bevel-gear or wheel, *c*, and *d* designates a pinion engaging therewith, and mounted on a short counter-shaft, *d'*.

E designates a shaft journaled in the frame 5 *B*, and receiving rotary motion from a belt, *E'*, passing over a pulley, *E*², upon it. This belt, as here shown, is driven from the shaft *A'* of the bed; but it might receive motion from any other shaft.

10 Upon the opposite end of the shaft *E* is a crank, *e*, the crank-pin or wrist-pin of which may be adjustable to vary its throw, and this crank, by means of a rod, *e'*, imparts a vibratory motion to an arm, *e*², loosely mounted on the shaft *d'*.

15 Upon the shaft *d'* is a ratchet-wheel, *d*², and the arm *e*² carries a pawl, *e*³, which takes into the teeth of said wheel *d*², and so imparts an intermittent rotary motion continuously in 20 one direction to the shaft *d'*, and through the wheels *e* *d* to the bottom plate, *C'*. Other mechanism might be used for rotating the bottom *C'*. The body *C* of the sand box or reservoir is approximately circular; but in its 25 side is represented an angular gap or recess, *C*², in one side or wall of which is a delivery-opening, *f*, which is regulated by a vertically-movable gate, *f'*. The gate may be adjusted up or down to vary the size of the opening *f* 30 and regulate the quantity of sand delivered, and may be secured in different positions by a bolt, *f*², or otherwise. Except for the delivery-opening *f*, the lower edge of the body *C* fits quite snugly against the bottom *C'*, so 35 that sand cannot escape in any quantity, except at said delivery-opening. The other wall, *g*, of the gap or recess *C*² forms a scraper, and it is provided with a continuation or extension, *g'*. (Best shown in Fig. 2.) As the bottom *C'* turns in the direction of the arrow, Fig. 2, 40 the sand or other abrading material escapes from the opening *f* in greater or less quantities, according as the opening is large or small, and as the sand comes against the 45 scraper *g* *g'* it is pushed off and delivered onto the bed *A*.

Referring now to Figs. 3 and 4, *C* designates the body of the sand box or reservoir, and *C'* designates the bottom thereof. The 50 body is intended to be secured in a fixed position to the frame *B*, and the bottom here shown consists of an endless apron or belt, which is mounted on rollers *F* *F'*.

Upon the shaft of the roller *F'* is secured a 55 ratchet-wheel, *d*², and at the side of said wheel is an arm, *e*², which carries a pawl, *e*³, engaging with the wheel, and to which a vibratory motion is imparted by a connecting-rod, *e'*, which is operated from a crank, *e*, upon a 60 shaft, *E*. The crank-pin of this crank may be adjustably secured, as before described, so as to afford provision for varying its throw of the crank, and the shaft *E* derives its rotary motion from the movement of the machine itself, 65 as before described.

In one side of the body *C* of the sand box or reservoir is a delivery-opening, *f*, which is

provided with an adjustable gate, *f'*, secured in place by bolts *f*². By adjusting this gate the quantity of sand allowed to escape may be 70 varied, and the sand carried off by the belt or apron *C* is deposited in a hopper, *G*, which delivers it near the center of the bed. We have not shown the bed in these figures; but it is arranged and operated as before described 75 with reference to Figs. 1 and 2.

Referring now to Fig. 5, *C* designates the body, and *C'* the separated bottom, of the sand box or reservoir. The bottom here shown consists simply of a plate supported upon 80 rollers *h*, and it has a reciprocating motion imparted to it by a connecting-rod, *e'*, operated by a crank, *e*, upon a shaft, *E*, which may be rotated by any suitable gearing deriving motion from the machine itself. The body 85 *C* has outlet-openings *f* in opposite sides, which are controlled by adjustable gates *f'*, and adjacent to the said outlet-openings are hinged scrapers *i*, which act alternately to scrape the sand from the bottom *C'* as it is reciprocated. 90 For example, as the bottom is moved toward the right the sand escapes from the right-hand opening, and the left-hand scraper removes the sand and delivers it into the hopper *G*; but when the bottom moves toward the left 95 the sand will escape from the left-hand opening, and will be removed by the scraper on the right-hand side of the body *C*.

Referring now to Fig. 6, *C* designates the body of the sand-box, and *C'* the separated 100 bottom thereof. In this example of our invention the bottom *C'* is fixed and the body *C* is reciprocated. The body is supported on rollers or wheels *j*, which run on a track, *j'*, and is reciprocated by a rod, *e'*, operated by 105 a crank, *e*, on a shaft, *E*.

In opposite sides of the body *C* are outlet-openings *f*, and as the body is moved it leaves the sand behind it and removes the sand in front of it, delivering it into the hopper *G*. 110

For different situations the opening between the bottom and body of the sand-box may be varied as required, and we may employ a quick speed and large outlet-openings *f* or a 115 slower speed and smaller openings.

The adjustable gates *f'* afford provision for regulating these openings or closing them entirely.

We are aware that feeding apparatus and devices of various kinds have been employed 120 for feeding grain and other material to be ground or reduced through the runner of a rotary grinding-mill.

We are also aware that a sand hopper or box having an inclined bottom, in connection 125 with a pipe for supplying water to said hopper or box to wash the sand out, has been applied to a rotary rubbing or polishing bed. We do not claim either of these combinations of parts as of our invention.

130 By our invention we deliver the sand by mechanically-operated devices, and do not wash it down, and as the feeding apparatus derives motion from the bed or machine itself,

its rate of feeding will always be commensurate to the speed of the machine.

We claim—

1. The combination, with the rotating bed 5 of a stone rubbing or polishing machine, of a box or reservoir for the scouring or polishing material, arranged between the center of the bed and its periphery, and composed of a body and a separated bottom, and mechanism 10 deriving motion from the machine itself, for giving one of these elements a movement relatively to the other, substantially as herein described.

2. The combination, with the rotating bed 15 of a stone rubbing or polishing machine, of a box or reservoir for scouring or polishing material, arranged between the center of the bed and its periphery, and composed of a body and a separated bottom, and mechanism deriving 20 motion from the machine for giving the said bottom a movement continuously in one direc-

tion relatively to said body, substantially as herein described.

3. The combination, with the rotating bed 25 of a stone rubbing or polishing machine, of a box or reservoir for scouring or polishing material, arranged between the center of the bed and its periphery, and composed of a body and a bottom plate arranged below the lower end of the body, and affording a space between 30 it and the body for the escape of the scouring or polishing material, and mechanism deriving motion from the machine itself, for giving said bottom plate a rotary motion continuously in one direction, substantially as herein de- 35 scribed.

HUGH YOUNG.
